(57) **CLAIM**

The ornamental design for a terra-cotta panel for a sunscreen, as shown and described.

DESCRIPTION

FIG. 1 is a perspective view of the top, front and one end of a terra-cotta panel for a sunscreen according to a first embodiment showing my new design;

FIG. 2 is a front elevational view, the rear elevational view being identical thereto;

FIG. 3 is a top plan view thereof, the bottom plan view being identical thereto;

FIG. 4 is an end view of said one end thereof, the opposite end being identical thereto;

FIG. 5 is a perspective view of the top front and one end of a panel for a terra-cotta sunscreen according to a second embodiment;

FIG. 6 is a front elevational view thereof, the rear elevational view being identical thereto;

FIG. 7 is a top plan view thereof, the bottom plan view being identical thereto; and,

FIG. 8 is an end elevational view of said one end thereof, the opposite end being identical thereto.
